WHIP ROLL CONTROLLED LETOFF FOR LOOMS

Oscar V. Payne, Leicester, Mass., assignor to Crompton & Knowles Loom Works, Worcester, Mass., a corporation of Massachusetts

Application September 14, 1942, Serial No. 458,215

6 Claims. (Cl. 139—100)

This invention relates to improvements in loom letoffs and it is the general object of the invention to improve the operation of that type of letoff which is controlled by a movable whip roll.

In my prior Patent No. 2,184,059 I have shown a letoff mechanism employing a whip roll which is moved forwardly as warp is consumed against the action of a weight which tends to move the whip roll rearwardly to tension the warp. In that mechanism the warp beam is normally locked by an escapement mechanism geared to the beam and released whenever the weights reach a given height so that the warp beam is momentarily released and turns to pay off warp with an accompanying rearward movement of the whip roll. The weights are mounted on a lever connected to a rod passing downwardly through the brake shoe lever which alternately locks and releases the escapement mechanism. The rod is surrounded by a spring which presses downwardly on the brake shoe lever and has the upper end thereof adjustable by a nut on the rod. In the weaving of certain fabrics it is necessary to set the adjustment for the spring within very close limits to prevent excess movement of the escapement mechanism if the loom should happen to stop on front center when the warp threads are placed under a maximum tension.

It is an important object of my present invention to employ a fixed stop for the upper end of the spring instead of the nut on the rod shown in the aforesaid patent, and adjust the stop so that it will always cause the spring to exert sufficient downward force to hold the escapement mechanism locked regardless of variations in the vertical position of the rod which moves with the weights.

In the mechanism shown in the aforesaid patent the spring exerts an upward force which partly counteracts the downward force of the weights. The latter must therefore be relatively heavy since they must oppose the counter-effect of the spring as well as tension the warp. As the weighted lever rises in that mechanism the spring expands and its counter-effect is therefore lessened so that the net force exerted by the weights increases as the whip roll moves forwardly.

It is another object of my present invention to overcome the aforesaid variation in the counter force derived from the spring by utilizing a fixed stop against which the spring exerts its upward force independently of the weights. This change enables me to use lighter weights and at

the same time attain more uniform tensioning of the warp.

In the patented mechanism already mentioned the rod is provided with a collar below the brake lever and this collar will be spaced below the brake lever when the weights are down. As the weights rise the spring tension diminishes but its reduced value should be sufficient to hold the brake lever in locking position until the lever is positively lifted by the collar. At the start of upward motion of the collar, the spring is under a higher degree of compression than is actually required for its operation and this has been one factor which has made necessary the use of heavy weights in the former mechanism. The stop already mentioned as a part of my present invention permits the setting of the spring so that it exerts sufficient force to hold the brake lever in locking position throughout the upward movement of the collar with no reduction in that force. Since the downward force of the spring remains undiminished there is no likelihood that the brake shoe will slip before the collar engages the brake lever and the brake can release the escapement mechanism only during the time that the collar is positively lifted by the brake lever. This time interval is comparatively short and the spring in the present instance, being under increased compressive force at this time, acts promptly to restore the brake shoe to holding position when the weight descends.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of the lower rear part of a loom showing my invention, parts being in section and the weight being removed for the sake of clearness,

Fig. 2 is a rear elevation taken in the direction of arrow 2, Fig. 1,

Fig. 3 is a diagrammatic plan view taken in the direction of arrow 3, Fig. 2 on a reduced scale,

Fig. 4 is a detail vertical section through the spring and rod associated therewith on line 4—4, Fig. 1, and

Fig. 5 is a detail vertical section on line 5—5, Fig. 1, on an enlarged scale.

The loom frame 10 has a bracket 11 at each side thereof to support a gudgeon 12 on the warp beam 13. The gudgeons rotate in bearings 14 mounted one on each bracket 11 when the beam

turns to pay off warp. A second bracket 15 projecting rearwardly from each side of the loom carries a stud 16 on which an upstanding arm 17 is mounted for limited angular motion. The lower end of the arm has a stop finger 18 to abut part 19 of the bracket 15 to limit rearward motion, or motion to the left as viewed in Fig. 1, of the arm 17. Each side of the loom is provided with one of the arms 17 and together they support for rotation a whip roll 20 over which the warp W passes from the warp beam barrel 21 to the harness frames not shown.

Each bracket 15 has pivotally mounted thereon a lever 25 with an arm 26 which extends in front of the corresponding upright arm 17. A second arm 27 of lever 25 extends forwardly and is connected to a link designated generally at 28 in Fig. 3. Each lever 25 turns around a pivot stud 29 supported by the corresponding bracket 15. As shown in Fig. 3 levers 25 will be acted upon by the upright arms 17 to rock said levers in a counterclockwise direction about their pivots when the warp beam 20 moves forwardly by a force derived from the warp, thereby moving link 28 to the left as viewed in Fig. 3.

Link 28 has a rod head 30 attached by an adjustable connector 31 to a weight lever 32 located at one side of the loom and pivoted as at 33 to a small stand 34 bolted to adjacent bracket 15. The connector 31 is pivoted as at 35 to lever 32 at a point above the pivot 33, and a horizontal arm 36 of the weight lever is provided with a series of notches 37 to receive a rod 38 the lower end of which carries a series of weights 39. The number of weights and the point at which their force is applied to arm 36 may be varied to meet different warp conditions.

Assuming that the warp beam 13 is locked against rotation, the weights 39 act through lever 32, connector 31, link 28 and levers 25 to exert a rearward force on the arms 17, thereby tending to hold the whip roll 20 rearwardly. As weaving continues and the warp is consumed, the whip roll 20 will move forwardly and in doing so will rock levers 25 in a direction to exert a pull on connector 31 to the left as viewed in Fig. 2, thereby lifting arm 36 to raise the weights. When the beam is unlocked by mechanism to be described it can turn to feed warp, at which time the weights descend to move the whip roll rearwardly and maintain warp tension substantially undiminished.

The locking mechanism for the warp beam includes reduction gearing and an escapement device together with a lock for the latter. As shown in Fig. 2 a relatively large gear 45 is rigid with the warp beam and meshes with a pinion 46 fastened to a shaft 47 rotatably mounted in the lower part of adjacent bracket 11. A gear 48 fast on shaft 47 and larger than the pinion meshes with a small pinion 49 rotating about a stud 50 also supported by the bracket 11. Fast with the pinion 49 is a gear 51 which meshes with a small pinion 52 rotatable on another stud 53 carried by the bracket 11. By the gearing just described the desired ratio can be obtained between pinion 52 and the warp beam.

By means of the gearing just described pinion 52 would rotate and permit gradual turning of the warp beam with loss of tension unless some provision were made for temporarily locking the pinion 52 and providing for its periodic release as required by the demands on the warp. This temporary locking is provided by an escapement device including a star wheel 60 fast with pinion

52 and having triangular teeth 61 the sides of which are straight and may be disposed at equal angles with respect to a radius from stud 53 passing through the point of the tooth. I do not wish to be held to the particular shape of tooth shown in Fig. 1 but have found that teeth of the shape shown therein operate satisfactorily.

The escapement comprises a rocking plate 70 having a hub 71 mounted on a stud 72 supported by the bracket 11. Secured to the plate 70 are upper and lower escapement teeth 73 and 74, respectively, which rock about stud 72 and have such relation with respect to the star wheel that when the plate 70 is unlocked and rocks in one direction, for instance to the left, Fig. 1, the top tooth 73 will pass down into the notch between two adjacent teeth while the tooth 74 will move out of the notch it previously occupied and permit the star wheel to turn. When tooth 73 reaches the bottom of its notch the inclined surface of the next tooth, being urged toward tooth 73 by beam pressure, will reverse the motion of plate 70 to permit continued turning of the star wheel. This will continue so long as plate 70 is unlocked and the warp beam exerts a force on the star wheel. Each complete back and forth motion of plate 70 permits an angular motion of the star wheel equal to the angular distance between adjacent teeth 61, and during this period the warp beam turns in a direction to feed warp.

In order to lock and release the escapement alternately during loom operation the bottom of plate 70 is provided with an arcuate rib 80 having a surface 81 concentric with stud 72. A shoe 82 faced with an anti-friction material 83 is pivoted as at 84 to a lever 85 free to swing on shaft 47. Arm 86 of lever 85 extends to the right, Fig. 1, and has extended therethrough the lower end of a vertical rod 87 to which is secured an adjustable stop collar 88 under arm 86. The lower end of a compression spring 89 pushes down on arm 86 while its upper end presses against a sleeve 90 surrounding the rod 87. The top of the rod has a head 92 pivoted on a stud 93 supported in the weight lever 32. By this latter connection the weights 39 and the rod move vertically together when arm 36 moves.

The matter thus far described may be the same as the corresponding matter set forth in my prior Patent No. 2,184,059.

My present invention relates to means for holding the upper end of spring 89 in a substantially fixed position as the weight rises. Any convenient means for accomplishing this result may be used but I have shown herein an adjustable stop which is readily adaptable to the form of let-off mechanism shown in my previously mentioned patent.

The escapement mechanism is inclosed in a housing defined partly by a rib 100 on the bracket 11 and partly by a removable cover 101. In the past the cover has been held against the rib 100 by a bolt threaded into a tapped hole in the bracket 11 and this previously used tapped hole is a convenient means for holding the adjustable stop for the upper end of the spring. As shown particularly in Fig. 5 I provide an angle stop 105 having a horizontal arm 106 formed with a slot 107 narrow enough to pass the rod 87 but not large enough to receive the sleeve 90. The vertical arm 110 of the stop has a vertical slot 111 therein which receives a screw 112 tapped into a boss 113 already present on those types of mechanisms made according to my prior patent. This screw is provided with a screwdriver

slot 114 and has a nut 115 drawn tightly against arm 110 to hold the stop 105 in vertically adjusted position against the bracket 11. The screw is provided with a second nut 116 which holds the thin casing 101 in place. The nut 116 can be released for removal of the casing 101 without disturbing the setting of the stop 105.

The operation of the let-off mechanism set forth herein is largely the same as that shown in the previously mentioned patent except for the action of spring 89 on lever 86. Previously the upper end of the spring rose and fell with the rod 87 and the downward force which it exerted was lessened as the weight arm 36 rose. In the present instance, on the other hand, the upper end of the spring is held in an adjusted but fixed position without regard to the position of collar 88. The parts will be set so that when collar 88 is spaced below lever 86, the spring pressure will be sufficient to hold the shoe 82 against the plate 70 and prevent operation of the escape mechanism. As the arm 36 rises and collar 88 approaches lever 86 this downward pressure of the spring remains the same, and when collar 88 ultimately engages lever 86 and arm 36 continues to rise, lever 86 will be rocked in a counter-clockwise direction as viewed in Fig. 1 to move the brake shoe downwardly and thereby release the escape mechanism. This upward motion of the right end of lever 86 as viewed in Fig. 1 causes an increase in the compression of spring 89 and as the escapement permits paying-off of warp and the whip roll moves rearwardly the spring will expand downwardly, and being under maximum compression at this time, will promptly return the brake shoe to holding position as soon as this action is permitted by descending collar 88. The spring will never expand, however, to a point where it will be too weak to hold the brake shoe tightly against the web 80. Thereafter the rod 87 and collar 88 can continue to move downwardly without effecting the force exerted by the spring on lever 86. A lateral foot 120 on stop 105 engages a vertical part of rib 100 to prevent turning of the stop about screw 112 as an axis.

It will be apparent that the spring 89 as controlled by the stop set forth herein does not exert an upward force on rod 87, and the weights on arm 36 are therefore not counter-balanced in part as previously, and for this reason a smaller amount of weight on the arm 36 may be used. When the stop 105 is properly set to cause the spring to maintain the brake shoe 82 in holding position the spring will always be able to exert the required force to prevent operation of the escapement mechanism during that part of the upward motion of rod 87 prior to engagement of collar 88 with lever 86.

From the foregoing it will be seen that I have provided simple means for controlling the escape mechanism of a loom let-off by which the spring 89 exerts a downward force on lever 86 without exerting a counter-balancing upward force on lever 36. As a result of the use of stop 105 a smaller amount of weight on lever 36 can be used than formerly and there is no reduction in the force exerted on brake shoe 82 as rod 87 rises. Also, the maximum compressive force ever exerted on spring 89 is only slightly more than that required to hold the escape mechanism and the brake shoe 82 is subjected to a much more uniform range of forces than heretofore.

Having thus described my invention it will be seen that changes and modifications may be

made therein by those skilled in the art without departing from the spirit and scope of the invention and I do not wish to be limited to the details herein disclosed, but what I claim is:

- 5 1. In a let-off for a loom having a warp beam to supply warp threads which pass over a movably mounted whip roll the position of which determines the tension of the warp thread, the warp threads tending by their tension to turn the warp beam, an escapement mechanism connected to the warp beam which when unlocked permits the warp to turn the beam, a brake to arrest the escapement mechanism to prevent turning of the warp beam and movable to release the escapement mechanism, a weight operatively connected to the whip roll to resist movement thereof in a direction to lower warp tension, and control mechanism for the brake including means to move said brake to releasing position when the weight reaches a given point in the upward movement thereof, and means to exert a constant force on the brake to hold the latter in arresting position with respect to the escapement mechanism before the weight in 10 the upward movement thereof reaches said given point.
- 15 2. In a let-off for a loom having a warp beam to supply warp threads which pass over a movably mounted whip roll the position of which determines the tension of the warp thread, the warp threads tending by their tension to turn the warp beam, an escapement mechanism connected to the warp beam which when unlocked permits the warp to turn the beam, a brake to arrest the escapement mechanism to prevent turning of the warp beam and movable to release the escapement mechanism, a weight operatively connected to the whip roll to resist movement thereof in a direction to lower warp tension, and control mechanism for the brake including means to move said brake to releasing position when the weight reaches a given point in the ascent thereof, and means to exert a constant force on the brake to hold the latter in arresting position with respect to the escapement mechanism before the weight in 20 the upward movement thereof reaches said given point.
- 25 3. In a let-off for a loom having a warp beam to supply warp threads which pass over a movably mounted whip roll the position of which determines the tension of the warp thread, the warp threads tending by their tension to turn the warp beam, an escapement mechanism connected to the warp beam which when unlocked permits the warp to turn the beam, a brake to arrest the escapement mechanism to prevent turning of the warp beam and movable to release the escapement mechanism, a weight operatively connected to the whip roll to resist movement thereof in a direction to lower warp tension, and control mechanism for the brake including means to move said brake to releasing position when the weight reaches a given point in the ascent thereof, and means to exert a constant force on the brake to hold the latter in arresting position with respect to the escapement mechanism before the weight in 30 the upward movement thereof reaches said given point.
- 35 4. In a let-off for a loom having a warp beam to supply warp threads which pass over a movably mounted whip roll the position of which determines the tension of the warp thread, the warp threads tending by their tension to turn the warp beam, an escapement mechanism connected to the warp beam which when unlocked permits the warp to turn the beam, a brake to arrest the escapement mechanism to prevent turning of the warp beam and movable to release the escapement mechanism, a weight operatively connected to the whip roll to resist movement thereof in a direction to lower warp tension, and control mechanism for the brake including means to move said brake to releasing position when the weight reaches a given point in the ascent thereof, and means to exert a constant force on the brake to hold the latter in arresting position with respect to the escapement mechanism before the weight in 40 the upward movement thereof reaches said given point.
- 45 5. In a let-off for a loom having a warp beam to supply warp threads which pass over a movably mounted whip roll the position of which determines the tension of the warp thread, the warp threads tending by their tension to turn the warp beam, an escapement mechanism connected to the warp beam which when unlocked permits the warp to turn the beam, a brake to arrest the escapement mechanism to prevent turning of the warp beam and movable to release the escapement mechanism, a weight operatively connected to the whip roll to resist movement thereof in a direction to lower warp tension, and control mechanism for the brake including means to move said brake to releasing position when the weight reaches a given point in the ascent thereof, and means to exert a constant force on the brake to hold the latter in arresting position with respect to the escapement mechanism before the weight in 50 the upward movement thereof reaches said given point.
- 55 6. In a let-off for a loom having a warp beam to supply warp threads which pass over a movably mounted whip roll the position of which determines the tension of the warp thread, the warp threads tending by their tension to turn the warp beam, an escapement mechanism connected to the warp beam which when unlocked permits the warp to turn the beam, a brake to arrest the escapement mechanism to prevent turning of the warp beam and movable to release the escapement mechanism, a weight operatively connected to the whip roll to resist movement thereof in a direction to lower warp tension, and control mechanism for the brake including means to move said brake to releasing position when the weight reaches a given point in the ascent thereof, and means to exert a constant force on the brake to hold the latter in arresting position with respect to the escapement mechanism before the weight in 60 the upward movement thereof reaches said given point.
- 65 7. In a let-off for a loom having a warp beam to supply warp threads which pass over a movably mounted whip roll the position of which determines the tension of the warp thread, the warp threads tending by their tension to turn the warp beam, an escapement mechanism connected to the warp beam which when unlocked permits the warp to turn the beam, a brake to arrest the escapement mechanism to prevent turning of the warp beam and movable to release the escapement mechanism, a weight operatively connected to the whip roll to resist movement thereof in a direction to lower warp tension, and control mechanism for the brake including means to move said brake to releasing position when the weight reaches a given point in the ascent thereof, and means to exert a constant force on the brake to hold the latter in arresting position with respect to the escapement mechanism before the weight in 70 the upward movement thereof reaches said given point.
- 75 8. In a let-off for a loom having a warp beam to supply warp threads which pass over a movably mounted whip roll the position of which

determines the tension of the warp thread, the warp threads tending by their tension to turn the warp beam, an escapement mechanism connected to the warp beam which when unlocked permits the warp to turn the beam, a brake to arrest the escapement mechanism to prevent turning of the warp beam and movable to release the escapement mechanism, a weight operatively connected to the whip roll to resist movement thereof in a direction to lower warp tension, and control mechanism for the brake including a brake releaser movable through a given range during operation of the letoff and operative at an intermediate point in said range to move the brake to releasing position, a spring having one end operatively connected to the brake and the other end fixed, said spring normally under a given degree of deformation and effective to exert a constant force on the brake to hold the latter in arresting position relatively to the escapement mechanism before said releaser reaches said given point, and said releaser after passing said point causing increased deformation of the spring and causing the spring to exert an increased force on the brake.

5. In a letoff for a loom having a warp beam to supply warp threads which pass over a movably mounted whip roll the position of which determines the tension of the warp thread, the warp threads tending by their tension to turn the warp beam, an escapement mechanism connected to the warp beam which when unlocked permits the warp to turn the beam, a brake to arrest the escapement mechanism to prevent turning of the warp beam and movable to release the escapement mechanism, a weight operatively connected to the whip roll to resist movement thereof in a direction to lower warp tension, and control mechanism for said brake including a rod movable upwardly with the

weight, a spring normally under a given degree of deformation and acting on the brake tending to hold the latter in arresting position relatively to the escape mechanism, and a fixed stop for said spring tending to prevent movement of the latter in a direction to release the brake, said rod during movement thereof as the weight ascends first releasing the brake and thereafter increasing the deformation of the spring to increase the tendency of the latter to move the brake toward arresting position relatively to the escapement mechanism.

6. In a letoff for a loom having a warp beam to supply warp threads which pass over a movably mounted whip roll the position of which determines the tension of the warp thread, the warp threads tending by their tension to turn the warp beam, an escapement mechanism connected to the warp beam which when unlocked permits the warp to turn the beam, a brake to arrest the escapement mechanism to prevent turning of the warp beam and movable to release the escapement mechanism, a weight operatively connected to the whip roll to resist movement thereof in a direction to lower warp tension, and control mechanism for the brake including a rod movable upwardly with the weight and capable during the ascent thereof to move the brake to releasing position, a compression spring surrounding the rod and having the lower end thereof engaging the brake to hold the latter normally in arresting position, and a fixed stop for the upper end of the spring, said rod in the ascent thereof subsequent to movement of the brake to releasing position causing increased compression of said spring to cause the latter to exert an increased force on the brake tending to move the latter toward arresting position.
